UNITED STATES PATENT OFFICE.

FREDERICK B. BROWNELL, OF ST. LOUIS, MISSOURI.

PASSENGER-VEHICLE.

SPECIFICATION forming part of Letters Patent No. 247,608, dated September 27, 1881.

Application filed April 2, 1881. (No model.)

To all whom it may concern:

Be it known that I, FREDERICK B. BROWNELL, of the city of St. Louis, in the State of Missouri, have invented a certain new and useful Improvement in Passenger - Vehicles, of which the following is a full, clear, and exact description, reference being had to the accompanying drawings, making part of this specification.

10 My improvement relates to that class of passenger-vehicles which are convertible into summer or winter conveyances, according to the season, and which can be made weather-proof in time of rain when in their summer condition.

15 My invention consists, first, in providing a sash, or the marginal frame in which the sash is held, with supporting-studs extending from its corners in line with the top and bottom 20 bars of the frame, said studs sliding in grooves in the pillars or stiles at the sides of the window extending up beneath the roof, so that the sash can be raised and lowered, the pillars or stiles having a notch or a series of notches, 25 by which the sash can be held at any elevation by means of the lower studs resting in the notches.

30 My invention also consists in hanging to the lower edge of the sash or sash-frame (as the case may be) a frame or shutter which can be turned upon the hinges by which it is connected to the sash or frame, and its free edge connected to the top of the sash or frame. This shutter is applicable to that class of summer 35 vehicles where the entrances are at the sides between the seats, and the said shutter closes the space between the seats when down.

Figure 1 is a transverse vertical section of one half of a vehicle with side entrance to the 40 seats, showing the entrance closed by the sash and shutter, and showing the sash and shutter in their upper position in dotted or broken lines. The edge of the sash and shutter is shown in full lines in their lower position. Fig. 1^a is a like view on a larger scale. Fig. 2 is a similar view to that shown in Fig. 1 of a vehicle having closed sides below the windows and the entrances being at the end or ends. The sash is shown in its upper position 50 and in edge view. Fig. 2^a is a like view on a larger scale. Fig. 3 is a front view of a sash

with a central pane of glass and a series of slats at the sides. Fig. 4 is a front view of a sash and shutter as used in the style of vehicle shown in Fig. 1. Fig. 5 is a front view of a 55 sash as used in the style of vehicle shown in Fig. 2. Fig. 6 is a side view of one of the window stiles or pillars, showing the series of inclined notches for the support of the sash at any height desired. Fig. 7 is an enlarged detail 60 of one corner of the sash shown in Fig. 5.

A is the floor of a street-vehicle. B is the end of the same, and C side posts. D are the window stiles or pillars. In the sides of the pillars are grooves d, and in these grooves 65 work studs e, projecting from the corners of the sash or sash-frames. The grooves d are carried up above the tops of the pillars in the sides of strips or rafters D' beneath the roof F of the vehicle. As the sash is raised the 70 upper studs e travel up the grooves or channels d in the strips D', while the lower pair of studs travel up the parts of the grooves d in the pillars.

75 It will be understood that the grooves or channels d can be curved in any direction, and that the sash may be made rigid, as it is supported only on the studs at the four corners, and no part of the edge of the sash proper enters the grooves d.

80 The convex side of the groove or channel d may have a bead extending beyond the edge of the sash or sash-frame, so as to close the crack between the same and the pillar.

At the side of the channels d are notches d', 85 which receive the studs at the lower part of the sash when it is in its upper position, and hold it in this position, as shown in Fig. 2.

80 d' are notches at the side of the groove d (in the pillars) to receive the lower studs and sustain the sash at any elevation desired.

I do not confine myself to any particular form or construction of sash in connection with the studs e, although I have special features of construction, which are made the subject 95 of a special claim, and which features I will now describe.

E' is a marginal frame, from which project the studs e, and into which the central part, E, of the sash (or the sash proper) is fitted. 100 The part E is held in the frame E' by buttons e', or by other suitable fastenings. The object

of this construction is to enable the sashes to be changed to suit the season without removal of the supporting-frame E'. Thus a sash containing glass may be used for winter, (see Fig. 4,) or one containing slats, as shown in Fig. 5, may be used during hot weather. It will be seen that the change can be made by any one in a very short time.

In Fig. 3 the sash is shown without a marginal supporting-frame, E', and having a central pane of glass and with slats at the sides. This construction of glass and slats is equally applicable to the removable sashes shown in Figs. 4 and 5.

15. There is a large class of summer vehicles in which the entrances are all along the sides in the spaces between the seats. In rainy weather, especially when accompanied by wind, the water enters through these spaces. To overcome this difficulty I provide any style of open-sided vehicle with sashes E, to whose lower edge is hung a sash or shutter, G, that reaches from

the lower edge of the sash to the floor of the vehicle, as seen in Fig. 1. In this figure the upper position of the sash and shutter is indicated in dotted or broken lines, the free edge of the shutter being turned up and attached to the upper part of sash E by any suitable fastening, as g.

I claim herein as new and of my invention— 30

1. In a passenger-vehicle, the combination, with a sash having horizontal studs in line with the upper and lower bars, of the pillars or stiles D, extending to the roof of the car, and provided with grooves or channels d and 35 notches d', for the purpose set forth.

2. The combination, with a sash or shutter, E, supported on studs e, of the shutter G, hinged to the lower side of said sash, for the purpose set forth.

FREDERICK B. BROWNELL.
